UNITED STATES PATENT OFFICE.

ARTHUR K. HATHAWAY, OF AXTELL, NEBRASKA.

BLACKSMITH'S VISE.

SPECIFICATION forming part of Letters Patent No. 446,348, dated February 10, 1891.

Application filed April 19, 1890. Serial No. 348,621. (No model.)

To all whom it may concern:

Be it known that I, ARTHUR K. HATHAWAY, a citizen of the United States, residing at Axtell, in the county of Kearney and State of Nebraska, have invented certain new and useful Improvements in Blacksmiths' Vises; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of the invention is to make a blacksmith's foot-power vise specially adapted for use in welding a steel "lay" on the landside of a plow, the landside being properly held by the vise while the smith is 20 making the weld.

Figure 1 of the drawings is a plan view of my vise provided with the treadle mechanism which I use, and Fig. 2 a front elevation thereof with the post upon which it is secured.

25 In the drawings, A represents a post or support to which the vise B is attached. The vise consists of two jaws b b', the former movable back and forth on the base C and provided with the bottom rabbet b², in which fits 30 the bottom projection b³ on the jaw b'. The base C is integral with the fixed jaw, while on it slides the movable jaw, which has end grooves to embrace it, the base itself being bolted to the post A. By this construction of 35 the contacting faces of the jaw conformably

to the shape of a landside the latter may be held steadily in the desired position.

D represents a lever fulcrumed at d on the post A, pivoted at d' to the rear of jaw b, and provided with a hook d² at the lower end. 40 This hook engages a roll e, journaled between the prongs e' e' of the bar E, which is pivoted at one end to the post A and jointed at e² to the rod F, whose lower end is pivoted to the front end of a treadle-lever G, fulcrumed to 45 the support H. By pressing his foot on the treadle-lever G the rod F, bar E, and jaw-lever D are all raised, so as to clamp the landside between the jaws while the smith is making the weld so as to properly attach the lay to 50 the landside.

What I claim as new, and desire to protect by Letters Patent, is—

The combination, with the sliding jaw b of a blacksmith's vise, of the lever D, fulcrumed 55 at d, pivoted to the back of said jaw at d' and provided with the hook d² at its lower end, the bar E, pivoted to the post A at one end and carrying between prongs e' e' a roll e, which engages said hook d², the rod F, and the 60 treadle G, said rod being end-pivoted to bar E and treadle G, as and for the purpose set forth.

In testimony whereof I affix my signature in presence of two witnesses.

ARTHUR K. HATHAWAY.
